UNITED STATES PATENT OFFICE

131,030

DESIGN FOR COMBINED HANDLES, ESCUTCHEONS, AND CORNER PLATES FOR A CASKET OR SIMILAR ARTICLE

Harold O. Utter, Richmond, Ind.

Application September 16, 1940, Serial No. 95,102

Term of patent 3½ years

To all whom it may concern:

Be it known that I, Harold O. Utter, a citizen of the United States, residing at Richmond, in the county of Wayne and State of Indiana, have invented a new, original, and ornamental Design for Combined Handles, Escutcheons, and Corner Plates for a Casket or Similar Article, of which the following is a specification, reference being had to the accompanying drawings, forming a part thereof.

Figure 1 is a fragmentary plan view of the combined handles, escutcheons and corner plates for a casket, embodying my new design;

Figure 2 is an elevational view thereof;

Figure 3 is a fragmentary elevational view taken from the left in Figure 1;

Figure 4 is an enlarged plan view of one of the corner plates of Figure 1;

Figure 5 is an enlarged side elevational view thereof;

Figure 6 is an enlarged plan view showing the center escutcheon of Figure 1, and a portion of the handle; and

Figure 7 is an enlarged elevational view of one of the corner plates of Figure 1 and a portion of the handle.

I claim:

The ornamental design for combined handles, escutcheons, and corner plates for a casket or similar article, substantially as shown.

HAROLD O. UTTER
